OSKAR SEITZ, OF BADEN, SWITZERLAND, ASSIGNOR TO AKTIENGESELLSCHAFT BROWN, BOVERI & CIE, OF BADEN, SWITZERLAND, A JOINT-STOCK COMPANY OF SWITZERLAND

ELECTRIC CURRENT RECTIFIER

Application filed July 23, 1930, Serial No. 470,199, and in Germany July 26, 1929.

This invention relates to improvement in electric current rectifiers of the metallic vapor type and particularly to an improved construction of the tank and cathode container of such rectifiers.

In electric current rectifiers of the metallic vapor type in which the container through which the rectifying arc operates is constructed of metal, the holder for the cathode material is usually electrically insulated from the rectifying tank or cylinder. Ceramic material such as porcelain, when used as the insulation between the cathode well or container and the metallic rectifier tank, do not require any special protection against thermal stresses produced by the arc up to certain loads on the rectifier. The use of such insulators however requires special means for sealing the insulator and the tank in the vacuum-tight relation necessary to proper rectifier operation. As the capacity of rectifiers increases, the difficulty of securing the proper insulation also increases and porcelain cannot be used for manufacturing reasons as well as because of the excessive mechanical and thermal stresses encountered. Other insulating materials have been suggested in place of porcelain but such materials are all objectionable because of the necessity for special protective means against thermal stresses and the difficulty of securing a vacuum-tight seal between the several portions of the structure.

It is, therefore, among the objects of the present invention to provide a rectifier construction in which the use of porcelain and other ceramic insulators may be avoided for electrically insulating the cathode holder or well from the rectifier cylinder.

Another object of the invention is to provide a rectifier construction which does not require a special seal for the insulator between the cathode well and the rectifier cylinder.

Another object of the invention is to provide a rectifier construction in which the insulator between the cathode holder and the rectifier cylinder likewise serves as a seal and does not require special protective means against thermal stresses.

Objects and advantages, other than those

above set forth, will be apparent from the following description when read in connection with the accompanying drawing which fragmentarily illustrates an electric current rectifier of the metallic vapor type, in which the rectifying action takes place, in a metallic cylinder embodying the present invention.

Referring more particularly to the drawing by characters of reference, the reference numeral 1 designates a portion of a rectifier cylinder or tank which is double-walled to permit the circulation of a cooling medium therethrough and which is formed with an aperture 2 through the bottom portion of the tank. The aperture 2 is surrounded by spaced ribs 3 depending or extending downwardly from the bottom of the tank in spaced concentric relation. A holder or well 4 for the cathode material 6 is formed to be arranged with the tank 1 in such manner as to close the aperture 2 in the bottom portion thereof. The cathode well 4 is preferably made double-walled to permit connection with the double-walled tank thereby providing a path for the circulation of a cooling medium through both the space between the double walls of the tank and of the cathode well. The upper edge of the cathode well 4 is formed with channels 7 so arranged as to receive the ribs 3 descending from the tank 1 in such spaced relation as to form substantially the equivalent of a labyrinth gland. The rectifier tank 1 and the cathode well 4 are spaced and electrically insulated from each other by a gasket 8 of suitable resilient insulating material capable of forming a seal between the several portions. The insulating gasket 8 does not require any thermal protection against attachment of the cathode spot thereon or against contact with the mercury vapor for the reason that the labyrinth formed by the ribs 3 and the channels 7 prevent direct contact of the cathode spot and the mercury vapor with the gasket 8. The mercury vapor is condensed by contact with the several portions forming the labyrinth and collect in the channels 7 from which it drains back to the cathode 6 through apertures 9. The gasket 8 is cooled by contact with the cooled

surfaces of both the rectifier tank 1 and the cathode well 4 and the ribs 3 and channels 7 are so spaced as to avoid formation of a mercury contact therebetween. The gasket 5 is therefore both protected against thermal and mechanical stresses and is so arranged as to avoid the requirement for protection against contact with the cathode spot of the mercury vapor.

- 10 It will thus be seen that the present invention provides a rectifier construction in which the tank and cathode well are electrically insulated from each other by means which also serves as a seal without requiring special 15 means for protection against thermal stresses or attachment by the cathode spot. The size and capacity of the rectifier is thus no longer limited by the insulation of the cathode well and the sealing thereof. The danger of destruction of the insulator during operation 20 is avoided thereby increasing the operative safety of the rectifier and the construction and erection of the rectifier is materially simplified and cheapened.
- 25 Although but one embodiment of the present invention has been illustrated and described, it will be apparent to those skilled in the art that various changes and modifications may be made therein without departing from 30 the spirit of the invention or from the scope of the appended claims.

The invention claimed is:

1. In an electric current rectifier construction, a tank having an aperture through the bottom thereof, the portion of said tank defining the aperture being formed to provide descending ribs, a well for receiving cathode material and to close the aperture through said tank, the tank engaging edge of said 35 cathode well being formed with channels therein, the ribs and channels being arranged in interspersed noncontacting manner.
2. In an electric current rectifier construction, a tank having an aperture through the bottom portion thereof, the portion of said tank defining the aperture being formed to provide descending ribs, a well for receiving cathode material and for closing the aperture through said tank, the tank engaging 45 edge of said cathode well being formed with channels therein, the ribs and channels being arranged in interspersed non-contacting relation, the channels being connected with the interior of said well by apertures through 50 the walls thereof, and a resilient gasket of electrical insulating material arranged between said tank and said well.
3. In an electric current rectifier, a double-walled tank having an aperture through the bottom portion thereof and forming a portion of a path for the circulation of a cooling medium therethrough, the portion of said tank defining the aperture being formed to provide descending ribs, a double-walled well 60 for receiving cathode material and for clos- 65

ing the aperture through said tank, said well forming a path for the circulation of a cooling medium therethrough, the tank engaging edge of said cathode well being formed with the channels therein, the ribs and channels 70 being arranged in interspersed non-contacting relation, the channels being connected with the interior of said well by apertures through the walls thereof, and a resilient gasket of electrical insulation material arranged 75 between said tank and said well.

In testimony whereof I have hereunto subscribed my name this 14th day of July, A. D. 1930.
